SIGNAL AND CONTROL SYSTEM FOR
ELEVATORS

Edgar M. Bouton, Park Ridge, Ill., and William F. Eames, Edgewood, Pa., assignors to Westinghouse Electric Elevator Company, Chicago, Ill., a corporation of Illinois

Application September 9, 1933, Serial No. 688,784

38 Claims. (Cl. 187—29)

Our invention relates to signal and control systems for elevators and more particularly to such signal and control systems as may be employed for operating a bank of elevator cars.

5 One object of our invention is to provide a signal and control system which will promote the answering of calls and the loading and unloading of passengers in the most prompt and efficient manner.

10 Another object is to give the attendants on the elevator cars such control over their cars as will result in handling the traffic most efficiently.

Another object is to cause the stopping of any car to take on a prospective passenger to be directly responsive to the action of a passenger in pressing a button to make a car stop for him.

15 A further object is to provide a system in which a passenger's stop-signal will stop only one car of a bank of cars and that car will be the nearest 20 car approaching in the direction in which the passenger desires to travel.

25 A still further object is to provide an elevator system in which, when a prospective passenger presses a call button to make a car stop for him in the direction he desires to travel, he will immediately receive a (car will stop) signal from the nearest car approaching in that direction, so that he may walk at once to the hatchway door for that car and be ready to step aboard as the 30 door opens.

It is also an object of our invention to provide a signal and control system which will inherently tend to keep the cars of a group properly spaced to obtain more efficient handling of passengers.

35 In order to accomplish these and other objects, we have provided an elevator system embodying a group of cars and a signal and control system therefor having the following characteristics and functions.

40 Each car in the group may be started by means of a car switch in the car and may be stopped by push buttons in the car or by push buttons at the floor landings. Each car has its own stopping floor buttons as well as its own car buttons and car switch. That is, a plurality of "stop" push buttons will be disposed at each floor, an "up" 45 button and a "down" button for each car.

Each button will be provided with an arrow arranged to be illuminated. The arrow will point 50 in the direction of the motion of the car that will stop in response to that button. That is, for an "up" button the arrow will point upwardly and for a "down" button the arrow will point downwardly.

55 At any given time at any given floor only one

"up" direction and one "down" direction button will be illuminated, indicating the buttons for the nearest approaching cars in the respective directions.

The illumination of the arrows will be controlled 5 by the cars. Each car will illuminate all the arrows at all the floors in advance of its motion, but only up to the floor corresponding to the car ahead.

When a car approaches the terminal which the 10 car ahead has left, the former car will light its own arrows to the terminal showing the present motion and also its own arrows away from the terminal showing the motion of the first named car up to the second mentioned car. That is, the 15 signal zone indicated by lighted arrows for the first named car will extend from that car to the terminal and away from the terminal to the leading car. A floor button will be effective to register a call only while its arrow is illuminated. 20

When an illuminated button at a floor is pressed to register a call, the floor lantern at that floor for the car corresponding to that button and for the corresponding direction will light at once regardless of how far the car is from that floor, to 25 indicate to the passenger that his call has been registered and which car will answer it. The floor lantern will remain lighted until the car leaves that floor.

The floor lantern at any floor for any car will 30 light when that car stops at the floor, as the result of an operation of a push button in the car. For this reason, two floor lanterns showing the same direction of travel may be lighted at any given floor, if one car stops for a hall call and 35 the other for a car call.

A car may be prevented from stopping to answer a floor call, by the operator pressing a bypass button in the car. When this occurs, floor calls registered on the bypassing car will be 40 transferred to the next following car at the time the former passes the floor at which the call is registered, thus only the bypass button and only the motion of the car transfers the call. The bypass button does not prevent a car stopping 45 in response to calls registered on the car buttons.

When the car attendant presses the bypass button, the illuminated arrows associated with the floor buttons for that particular car at floors 50 in advance of the car's motion will be extinguished and those for the next following car will become illuminated. Thus any subsequently registered call in advance of the car's position will be registered on the following car. However, the 55

- floor lanterns lighted at floors where calls were registered previous to the bypass operation will remain lighted until the car passes that floor when they will be transferred to the following car.
- 5 For a better understanding of the invention reference may be had to the accompanying drawings in which;

Figure 1 is a diagrammatic representation of an elevator installation embodying our improved 10 signal and control system.

Fig. 2 is a view in front elevation of a push button panel embodying a modification of the floor push button panel included in Fig. 1.

Fig. 3 is a view in side elevation of the push 15 button panel shown in Fig. 2.

Figs. 4, 5 and 6 collectively constitute a diagrammatic representation, in what is known as the straight-line style, of the signal and control system employed in operating the elevator cars 20 shown in Fig. 1; and

Figs. 4a, 5a and 6a collectively constitute an explanatory illustration of the relays embodied in Figs. 4, 5 and 6.

The illustration of the relays in Figs. 4a, 5a 25 and 6a show them with their coils and contact members disposed on horizontal lines corresponding to their positions in the "straight-line" circuits of Figs. 4, 5 and 6 so that the reader may readily determine the identification of any relay, 30 the number and kind of its contact members and the position of its coil and its contact members in the "straight-line" circuits.

For convenience in reading the drawings, Fig. 5 35 should be placed under Fig. 4, Fig. 6 under Fig. 5, Fig. 4a beside Fig. 4, Fig. 5a beside Fig. 5 and under 4a, and Fig. 6a beside Fig. 6 and under Fig. 5a.

Referring more particularly to the drawings, 40 we have illustrated an elevator installation embodying two cars A and B for serving four floors or landings. The cars are suitably suspended by cables 11 and 12 which pass over hoisting drums 13 and B13 to suitable counterweights 15 and 16, respectively.

45 Although we have shown only two cars and a signal and control system therefore as applied to only four floors, it is to be understood that the system is equally applicable to any suitable 50 number of cars operating past any desired number of floors.

For convenience, the main relays included in the system are designated as follows:

55 V=High speed relay for car A.
Q=Brake relay for car A.
3D = Floor call registering relays energized upon the pressing of a floor button for car A. One for each car for each direction at each floor.
3U =

60 C=Car button holding or registering coils for push buttons in car A.

S=Floor button stopping relay for car A.
R=Car button stopping relay for car A.
E=Inductor relay for decelerating car A.
F=Inductor relay for stopping car A.
G=Slow down holding relay for car A.

70 UZ }=Zone relays (common to both cars).
DZ }=

DT }= Stop call transfer relays (common to
UT }= both cars).

75 DP }= Relays preventing more than one car re-
UP }= ceiving a registered stop call.

H=Bypass relay for car A.
J=Auxiliary bypass relay for up direction car A.

K=Auxiliary bypass relay for down direction car A.

N=Up direction preference relay for car A.

M=Down direction preference relay for car A.

The relays for car B are given the same designation as those for car A plus the letter B. The letters U and D indicate up and down direction. The prefix numerals indicate the floors. The suffix numerals indicate the contact members of the relays. For instance, 1BU designates the up floor call registering relay at the first floor for car B and 1BU1 designates one pair of the contact members of that relay.

Referring to the control system for car A as shown in Figs. 4 and 5, the hoisting drum 13 is directly coupled to an armature 17 of a hoisting motor 18, the field winding 19 of which is connected, for constant voltage energization, to a source of supply designated as the supply conductors L+ and L-.

A variable voltage system of control may be provided for operating the hoisting motor 18 wherein the armature 17 is connected in a loop circuit with the armature 21 of a generator 22. The generator is provided with a separately excited field winding 23 and a cumulative series field winding 24. A resistor R24 is connected in the circuit of the separately excited field winding 23 for stabilizing the operation of the generator. The armature 21 of the generator may be driven by a suitable driving motor 25 which may be connected to a suitable source of supply as represented by the conductors and switch 26.

A brake 5 operated by a brake magnet 6 is provided for applying a braking effect to the hoisting drum 13 when the car is brought to a stop, the brake magnet 6 being energized to release the brake 5 when the car is running and being deenergized to apply the brake 5 when the supply of power to the car is cut off.

The direction and speed of the hoisting motor 18 may be suitably controlled by controlling the direction and the value of the excitation current that is supplied to the separately excited field winding 23 of the generator 22.

The direction of the excitation current for the field winding 23 may be suitably controlled by means of an up direction switch U and a down direction switch D, while the value of the current supplied to the field winding may be controlled by means of a speed relay V.

The operation of the up direction and the down direction switches U and D, as well as the speed relay V, may be controlled by means of a car switch CS that is to be mounted on the car in position to be actuated by an attendant thereon. When the car switch CS is moved in a clockwise direction, its contact members b and e close thereby completing a circuit for energizing the up direction switch U which in turn closes its contact members U1 and U4, thereby completing a circuit for energizing the separately excited field winding 23 in a direction to operate the hoisting motor 18 to move the car upwardly. At the same time, the brake magnet 6 is energized to release the brake 5.

Upon a continued movement of the car switch CS in a clockwise direction, it closes its contact members e and a, thereby energizing the high-speed relay V to close its contact members VI and thereby eliminate the resistor R24 from the circuit of the separately excited field winding 23.

Any suitable means may be employed which will, when energized, automatically stop the car

A level with the floors it serves. As an example of such a means, we have illustrated the stopping means as including an automatic inductor landing system such as is disclosed in Patent 5 No. 1,884,446, issued October 25, 1932, to K. M. White and G. K. Hearn, assignors to Westinghouse Electric Elevator Company.

The inductor landing system for the car A includes a high-speed inductor relay E and a stopping inductor relay F for causing the car to be automatically decelerated from its high speed and brought to a stop at an exact level with the floor. These relays are mounted on the car A in position to cooperate with sets of inductor plates 1UF, 1DF, 2UE and 2DE of magnetic material mounted in the hatchway. For simplicity, only one set of inductors for one floor have been shown, but it will be understood that a set similar to that shown may be provided for each floor 10 served by the car intermediate the upper terminal landing and the lower terminal landing. A set corresponding to the inductor plates 1UF and 2UE may be provided for the upper terminal landing and a set corresponding to inductor plates 15 1DF and 2DE may be provided for the lower terminal landing.

As shown, each inductor relay is provided with two sets of contact members. The contact members E1 of relay E cooperate with inductor plate 20 2DE. The contact members E2 of relay E cooperate with plate 2UE. The contact members F1 of relay F cooperate with the inductor plate 1DF. The contact members F2 of inductor relay F cooperate with inductor plate 1UF. 25 The contact members just described are so connected with the car control circuits that when the inductor relays are energized to stop the car at the floor represented by the inductor plates, in the down direction, the contact members E1 30 first pass the inductor plate 2DE and are thereby opened to decelerate the car, and as the contact members F1 come opposite the inductor plate 1DF they open to stop the car level with the floor. The contact members E2 of relay E and 35 the contact members F2 of the relay F are opened by the inductor plates 2UE and 1UF, respectively, when the stop is to be made in the up direction.

Once the inductor relays are energized to slow 40 down the car to a stop, it is desirable to maintain them in that condition until they are operated to bring the car to rest. A slow down holding relay G is provided for this purpose.

In the elevator system illustrated in the drawings, the energization of the inductor relays on car A for stopping that car at a floor is effected either by a car button stopping relay R or by a floor button stopping relay S. The energization of either of these relays will, as the car nears 45 a floor at which a stop is to be made, energize the inductor relays and thereby cause the car to decelerate and stop at that floor.

The car button stopping relay R is controlled by push buttons in the car A; that is, the pressing of a car button by the car attendant will register a stop call, or in other words, initiate and maintain a circuit which will be completed as the car nears the floor corresponding to the button to thereby energize the stopping relay R 50 which will, in turn, energize the inductor relays to stop the car at that floor.

The stopping relay S is controlled by push buttons at the floor landings; that is the pressing of a floor button will register, or in other words, initiate and maintain a circuit which will 55

be completed as the car nears that floor and thereby energize the stopping relay S which will, in turn, energize the inductor relays to stop the car at such floor.

The push-buttons mounted in the car A to be operated by the car attendant when he desires to register stop calls to stop the car at the floors where passengers desire to get off are designated as A2 and A3, for the second and third floors respectively, no buttons being necessary for the lower terminal floor and the upper terminal floor because the car will be stopped by the usual and well-known limit switches (not shown), as it approaches these terminals.

The push buttons disposed at the floor landings to enable waiting passengers to register stop calls that will cause the car A to stop at their floor so that they may board it, are designated as follows: The up buttons for car A are marked as 1UA at the first floor, 2UA at the second floor 20 and 3UA at the third floor. The down floor buttons for car A are marked as 2DA at the second floor, 3DA at the third floor and 4DA at the fourth floor. Inasmuch as the car A does not go below the first floor, no down button is provided 25 for the first floor. Similarly, inasmuch as car A does not go above the fourth floor, no up button is provided for the fourth floor.

The control system for car B is the same as that just described for car A, there being a set 30 of car buttons B2 and B3 and also separate up floor buttons and down floor buttons at the floor landings for car B. The up floor buttons for car B are designated as 1UB at the first floor, 2UB at 35 the second floor, and 3UB at the third floor, no up floor button being shown at the fourth floor because the car does not go above the fourth floor. The down floor buttons for car B are designated as 2DB at the second floor, 3DB at the third floor and 4DB at the fourth floor, no down 40 button being shown for the first floor because car B does not go below that floor and is stopped thereat by the usual well-known limit switches.

Associated with the respective car push buttons are car push button holding or registering 45 relays 2C and 3C for car A; and 2BC and 3BC for car B. These relays operate to hold the car push buttons A2 and A3 in car A and B2 and B3 in car B in a depressed position after they are operated by the car attendants in making stops 50 from within the cars.

Associated with the floor push buttons for car A are stop call registering relays 1U, 2U and 3U for the up direction and 2D, 3D and 4D for the down direction. Similar registering relays 1BU, 2BU and 3BU are provided for the up direction floor buttons of car B and 2BD, 3BD and 4BD for the down direction. These relays operate to maintain a floor button circuit in a registered condition after that button is pressed until the 55 car answers the registered call by stopping at the floor. A cancellation coil is also mounted upon the body of each of these relays for the purpose of deenergizing it at the time the call is answered.

The up floor buttons and the down floor buttons for car A and the up floor buttons and the down floor buttons for car B at any one floor may be arranged as desired. However, we prefer to mount the floor buttons for car B at any floor beside the buttons for car A at that floor, as 60 shown in the push button panel 27 in Fig. 1. This push button panel may be said to include the up push button 2UA and the down push button 2DA for car A and the up push button 2UB and the down push button 2DB for car B at the 70 75

second floor. The panel is shown as provided with additional push buttons for other cars, although, for the sake of simplicity such other cars are not illustrated or described in the present system.

Inasmuch as each car has its own set of up buttons and down buttons at each floor, we have provided each button with an arrow arranged to be illuminated to inform the waiting passenger which button should be pressed to stop the nearest approaching car in the direction in which he desires to go. Although an arrow is provided for each button, only one button for each direction will be indicated by an illuminated arrow. Hence, when a passenger approaches the push button panel and desires to go to an upper floor, he will press the button indicated by the illuminated up direction arrow. Thereby the passenger will stop the nearest approaching car going up. Likewise, if a passenger desired to go to a lower floor, he will press the button indicated by the illuminated down direction arrow and thereby stop the nearest approaching down car.

25 The up direction arrows for car A (see Fig. 5) are designated as 30 for the first floor, 31 for the second floor and 32 for the third floor. The down direction arrows for car A are designated as 33 for the second floor, 34 for the third floor and 30 35 for the fourth floor. The up arrows for car B are designated as 36, for the first floor, 37 at the second floor, and 38 at the third floor. The down direction arrows for car B are designated as 39 for the second floor, 40 for the third floor, 35 and as 41 for the fourth floor.

In order that a waiting passenger may be informed or signalled, when he presses a floor push button, that his stop call has been registered and also which car approaching in the direction 40 in which he desires to go will make a stop at his landing, we have provided a plurality of signal or indicating devices, preferably electric lamps, which are mounted outside of the elevator shafts at the floor landings.

45 Each of the top and bottom floors is provided with a single one of these signal lamps or floor lanterns for each car; but each of the intermediate floors is provided with a pair of lanterns for each car, one serving to indicate that the 50 corresponding car is approaching in the down direction and will make a down stop at the floor, and the other that it is approaching in an up direction and will make an up stop. This signal is given immediately upon the pressing of the 55 button even though the car may be many floors away.

The floor lanterns for car A (see Fig. 5) are designated as follows: The up floor lantern at the first floor as 1ULA, the up floor lantern at 60 the second floor as 2ULA, the up floor lantern at the third floor as 3ULA; the down floor lantern at the second floor as 2DLA, the down floor lantern at the third floor as 3DLA and the down floor lantern at the fourth floor as 4DLA.

65 For car B (see Fig. 6) the up floor lantern at the first floor is designated as 1ULB, the up floor lantern at the second floor as 2ULB, the up floor lantern at the third floor as 3ULB, the down floor lantern at the second floor as 2DLB, the down floor lantern at the third floor as 3DLB and the down floor lantern at the fourth floor as 4DLB.

When a passenger presses a floor button corresponding to an illuminated arrow, the floor lantern of the nearest approaching car in the 75

direction he desires to go is lighted immediately to indicate to him that that car will stop for him and the hatchway door at which the stop will be made, so that he may at once walk to that hatchway door and be ready to get into the 5 car as soon as the door opens.

The direction arrows for any one car are arranged to be illuminated at all floors in advance of its motion, but only up to the floor corresponding to the car ahead; that is, the car 10 provides ahead of it a signalling zone defined by its arrows to indicate to waiting passengers at the floors in that zone that that car is approaching and will stop for them if they will press the floor buttons indicated by the illuminated arrows for that direction.

In order to illuminate the arrows in the signal zone in advance of the car, we have provided a plurality of zoning relays designated as 1UZ, 2UZ and 3UZ for the up direction, and 2DZ, 3DZ and 20 4DZ for the down direction. These zoning relays are common to both cars.

The zoning relays divide the complete round trip shaft travel of all cars into as many signal zones as there are cars operating. And they 25 then assign one zone to each car. The zone that is assigned to any one car is the zone in advance of that car's motion. The zone for each car is elastic and keeps moving along with the car, its end being determined by the position 30 of the next car ahead.

The floor push buttons for any given car which are effective to stop that car are only those at the floors included in that car's immediate signal zone; that is, a particular push button is 35 effective to operate only for that car whose zone includes that push button at that time.

A plurality of preventing relays 2DP, 3DP, 2UP and 3UP are provided for preventing more than one car receiving a stop signal from the floor 40 push buttons at any floor; that is, these relays prevent the registration of a stop call on any push button whose arrow is not illuminated. These relays are common to both cars.

At various times in the operation of the ele- 45 vator system, a car may be so loaded that the operator may desire to run past the outside stop calls at various floors. In order to accomplish this purpose, a by-pass push button 43 is mounted in car A and a similar by-pass button 44 is 50 mounted in car B. As long as a car attendant presses the by-pass button in his car, that car will not answer or stop at any floor button call, it will not illuminate its own indicating arrows, and it will prevent registration of stop calls on 55 its floor buttons while by-passing. As soon as the button is released, the car will again respond to outside calls, light its arrows, etc.

A by-pass relay H is provided for energization by the pressing of the by-pass button 43 in car 60 A to so modify the control circuits as to effect the various functions described in the by-passing of car A. Similarly, a by-pass relay BH is provided for energization by the pressing of the by-pass button 44 in car B.

When an attendant presses a by-pass button and thereby causes the car to pass a registered floor call without stopping, it is desirable to have such floor call transferred to the next following car. To provide for this signal transfer in an 70 automatic manner, we have provided signal transfer relays 2UT and 3UT for the up direction, and 2DT and 3DT for the down direction. These relays are common to both cars and are provided for only the second and third floor, no such relays 75

being provided for the terminal floors as it is obvious that each car must stop at the terminal floors regardless of stop calls.

As an aid in carrying out the automatic transfer of the floor stop signals, we have provided a plurality of auxiliary by-pass relays. The auxiliary by-pass relay for the down direction of car A is designated as J, that for the up direction of car A as K. The auxiliary by-pass relay for the down direction of car B is designated as BJ and that for the up direction of car B as BK.

In order that the various circuits for the push buttons, floor lanterns, and the relays heretofore mentioned may be connected at the correct time and in accordance with the position of the cars, the cars A and B are provided, respectively, with floor selectors FSA and FSB.

Upon referring to Fig. 1, it will be observed that the floor selector FSA comprises a vertically mounted base panel 46 upon which are secured suitable guide rails 47 for a pair of vertically movable cross-head members 48 and 49. The cross-head members are mechanically connected together by means of a chain 50 which passes over an idler sprocket 51 rotatably mounted on the base panel 46 and a driving sprocket 52 rotatably supported by means of a casing 53 mounted on the base panel 46.

The casing 53 contains suitable gearing (not shown) for transmitting the motion of a telemotor receiver 54 to the driving sprocket 52. The telemotor receiver 54 is operated by a telemotor transmitter 55 which is directly coupled to the shaft of the hoisting motor 18 and, therefore, operates in accordance with the movements of the car.

The floor selector FSA is so operated by the telemotor receiver and telemotor transmitter that the movements of the elevator car A are reproduced on a reduced scale by the movements of the cross-head members 48 and 49.

As is usual in floor selectors, a plurality of "up" brushes 60, 61, 62, 63, 64, 65, 65a, 66 and 67 (see Fig. 5) are so mounted on the "up" cross-head 48 as to move over and engage cooperating "up" contact segments 70, 71, 72, 73, 74, 75 and 76 on the face of the floor selector when the car is operated.

In a similar manner, a plurality of "down" brushes 80, 81, 82, 83, 84, 85, 85a, 86 and 87 are mounted on the "down" cross-head 49 in such manner as to engage a plurality of "down" contact segments 90, 91, 92, 93, 94, 95 and 96 on the face of the floor selector when the car is operated.

Therefore, as the cross-heads move up and down, the brushes engage the contact segments for various floors in accordance with the movements of the car; that is, there are contact segments for each floor and the brushes are operated to engage the contact segments corresponding to the floor at which the car is located.

The brushes engage their cooperating contact segments during both the up movements and the down movements. Therefore, in order to make the "up" brushes electrically effective only during upward movement of the car and the "down" brushes electrically effective only during downward movement of the car, we have provided a plurality of direction preference relays.

The "up" direction preference relay for car A is designated as N and the "down" direction preference relay as M.

The up preference relay N is so constructed and connected that the brushes on the "up" cross-head 48 are electrically effective as that cross-

head is moved downwardly on the selector by the upward movement of the car; that is, as the cross-head 48 moves downwardly it electrically and selectively connects the circuits for the floors in accordance with the movement of the car past the floors on its up trip, and disconnects the brushes during the upward movement of the cross-head 48 by the downward movement of the car.

The down preference relay M electrically connects the brushes on the down cross-head 49 with the floor circuits during the downward movement of the cross-head by the downward movement of the car, and disconnects them during the upward movement of the cross-head 49 by the upward movement of the car.

In other words, the down movement of the cross-head 48 reproduces the car's "up" movement. The down movement of the cross-head 49 reproduces the car's "down" movement.

The means for energizing the direction preference relays N and M in accordance with the direction of operation of the car comprise a pair of limit switches 56 and 57 disposed on the floor selector FSA. As the cross-head 49 completes its downward travel in connecting the "down" circuits, it strikes and opens the limit switch 56, thereby energizing the "up" preference relay N to connect the "up" side of the floor selector for the "up" trip of the car. When the "up" cross-head completes its downward travel in connecting the "up" circuits, it strikes and opens the limit switch 57 thereby energizing the "down" preference relay M to connect the down side of the floor selector for the down trip.

The group of contact segments 70 under the brush 60 lights the up floor lantern for car A when the car is stopped by an up registered car call.

The group of contact segments 71 under brush 61 feeds the illuminated arrows in the car's signal zone and lights the floor lanterns at floors at which stop calls are registered on the floor buttons. The brush 61 has a long bearing surface so as to bridge the gap between the contact segments as it passes from one to the other. This prevents blinking of the lights.

The group of contact segments 72 under brush 62 completes the circuit for cancelling the up floor button calls when they are answered.

The group of contact segments 73 under the brushes 63 and 66 are fed by the floor button registering relays for the purpose of energizing the floor button stopping relay when the car approaches a floor at which a stop is to be made in response to the pressing of an up floor button. When a call is to be transferred from this car to another car, the brush 63 is electrically disconnected to prevent energization of the stopping relay of this car, and brush 66 is electrically connected to brush 67 to effect energization of the floor button stopping relay of the following car.

The group of contact segments 74 under the brush 64 are energized by the car buttons so that the approach of the car to a floor corresponding to a floor for which a car button has been pressed will cause the energization of the car button stopping relay and thereby stop the car at that floor.

The group of contact segments 75 under the brushes 65 and 65a are the segments through 70 which the zoning relays are energized, in accordance with the position and movement of the car.

Ordinarily, one long brush might be employed to prevent flickering of the lighted arrows as the car moves from segment to segment, but the two

brushes 65 and 65a, instead of one long brush, are provided to prevent sneak circuits from the brushes of one car through the brushes of the other car to the zone relays, which are common to both cars. These brushes are electrically connected by the direction relay K when the car is making an up trip, so that the zone relays will be maintained while the car is passing from brush to brush but are electrically disconnected while the car is going down.

The group of contact segments 76 under the brush 67 serve to pick up a relay which energizes the contact segments 71 of all other cars to effect a transfer by reason of the operation of the bypass buttons. It may be noted here that the brushes 66 and 67 are disposed in an advanced position relative to the position of the brushes 62, 63, etc., so that they may be utilized in effecting a transfer of a stop call from the car they represent to the next approaching car. In practice, the distance of the advance may be any suitable amount such as may correspond to one-half floor travel of the car.

The group of "down" contact segments 90 to 96 disposed to be engaged by the brushes 80 to 87 on the "down" cross-head 49 are similar to those described for the "up" side of the floor selector except that they are arranged to complete the various "down" circuits when the car is traveling downwardly.

Inasmuch as the floor selector for car B is the same as that for car A, a detailed description thereof will not be given. However, it may be noted that the same designating numerals will be given to similar parts with the letter B in front to indicate that they are for car B instead of car A.

The system may be operated as follows:

Assume that car A is standing at the upper terminal and that car B is standing at the lower terminal. Assume also that only car A will be operated at present and that car B will be left standing at the lower terminal. The operation of car A will not be affected in any manner by car B standing at the lower terminal without being conditioned for operation.

The master switches 26 and 28 (Fig. 4) are closed to condition car A for operation.

The closing of the master switch 26 connects the driving motor 25 for energization by a suitable source of energy (not shown). The energization of the driving motor operates the generator 22 for supplying energy to the hoisting motor 18. However, inasmuch as the separately excited field winding 23 of the generator is not energized, no current flows through the circuit to the hoisting motor and it remains idle.

The closing of the master switch 28 prepares the control circuit for operating car A by energizing the field winding 19 of the hoisting motor 18, the "down" floor lantern or signal device 4DLA at the upper terminal, the down direction preference relay M, the auxiliary by-pass relay J for the down direction, and the holding or registering coils 3C and 2C for the push buttons in car A.

The circuit for the lighted lantern 4DLA extends from supply conductor L+ (Fig. 5) through the lamp, contact segment 100, brush 80, the contact members M4 of down direction preference relay M and the normally closed contact members V4 of the high-speed relay for car A to the supply conductor L.

The circuit for the down direction relay M 75 extends from supply conductor L+ (Fig. 4) to

conductor 101, the limit switch 56, the coil M and the normally closed contact members N1 of up direction preference relay N for car A to supply conductor L-.

The circuit for the auxiliary by-pass relay J 5 for the down direction extends from supply conductor L+ through conductor 101, the contact members M2 of down direction preference relay M, the coil J and the normally closed contact members H1 of the by-pass relay for car A to 10 supply conductor L-.

The circuit for the car button holding coils 3C and 2C extends from the supply conductor L+ through conductor 101, the coils 3C and 2C and the contact members M3 of relay M to the supply 15 conductor L-.

Inasmuch as the variable voltage system and the control system for operating car A have been placed in condition for operation, the car is now ready to be moved downwardly. To accomplish this purpose, the car attendant moves the car switch CS in a counter-clockwise direction to the first point, thereby energizing the down direction switch D for operating the hoisting motor by a circuit extending from the supply 25 conductor L+ (Fig. 4) through the contact members e and c of switch CS, the contact members U5 and F1, the coil D, the door and gate interlocks 102 and the coil Q of the brake relay for car A to the supply conductor L-.

The energization of the down direction relay D closes its contact members D5 to provide a self-holding circuit for itself and also closes its contact members D4, D2 and D3 for energizing the brake relay coil 6 and the separately excited field winding 23 of the generator 22.

The energization of the field winding 23 causes the generator 22 to supply current to the hoisting motor 18, which, in turn, operates the hoisting drum 13 to lower the car in the hatchway 40 (not shown).

The operation of the hoisting motor 18 also operates the telemotor 55 mounted on the shaft thereof for controlling the operation of the telemotor receiver 54, which, in turn, moves the cross-head 49 downwardly in accordance with the movement of the car. Thus the movement of the car switch to the first point c starts the car downwardly at a low speed comparable to the usual landing speed. The car switch is now advanced to engage its second point f to complete a circuit for energizing the high-speed relay V to run the car at its normal high speed. This circuit extends from the supply conductor L+ (Fig. 4) through the contact members e and f of car switch CS, the contact members E1 and the coil V to the supply conductor L-.

The energization of the high-speed relay V closes its contact members V1 to eliminate the resistance R24 from the circuit of the field winding 23 of the generator 22, thereby causing the variable voltage system to operate the car at high speed.

The energization of the speed relay V also closes its contact members V2 to complete a self-holding circuit for itself, which will cause the car to continue running at high speed until it is decelerated and stopped by the pressing of a push button in the car or by the pressing of a push button at one of the floors. Hence it is seen that the car is started by the car attendant closing the car switch CS and is stopped by the registration of calls on the push buttons. The car switch CS may be returned to its central or neutral point as soon as the car attains 75

desired speed, because its position has no effect on the stopping of the car.

The energization of the relay V also opens its contact members V4 (Fig. 5), thereby extinguishing the down floor lantern 4DLA for car A at the fourth floor as the car leaves that floor.

Car A is now on its downward trip at high speed and it will be assumed that the car attendant presses the car button A3 to stop the car at the 10 third floor. The pressing of the button A3 causes it to be held in its closed position by the energized holding coil 3C, in which position its contact members close a circuit for supplying energy to the contact segment 103. As the car approaches the third floor, the floor selector brush 34 engages the energized contact segment 103, thereby energizing the car button stopping relay R of car A. The circuit extends from supply conductor L+ through the contact members of push 20 button A3, contact segment 103 of the floor selector, the brush 34, the contact members M6 of down direction relay M and the coil of stopping relay R to the supply conductor L-.

The energization of the stopping relay R closes 25 its contact members R1 (Fig. 4) thereby energizing the slowdown holding relay G and the decelerating inductor relay E by a circuit extending from the supply conductor L+ through conductor 104, the contact members R1 to a point where it 30 divides and extends in parallel through the coils G and E, thence through the contact members Q2 to the supply conductor L-.

The energization of the slowdown holding relay G closes its contact members G1, thereby providing a self-holding circuit for the relays G and E.

The energization of the decelerating inductor relay E prepares that relay to be operated when the car arrives within such a predetermined distance of the third floor as to cause the relay E to come opposite the cooperating decelerating inductor plate 2DE for the third floor.

Assuming that the inductor relay E now comes opposite the inductor plate 2DE, the energized 45 condition of the relay causes it to be operated by its position adjacent to the plate to open its contact members E1, thereby deenergizing the high-speed relay V to decelerate the car.

The deenergization of the high speed relay V 50 opens its contact members V1 (Fig. 4), thereby reinserting the resistor R24 in the circuit of the generator field winding 23 to cause the car to be decelerated from its high speed to its landing speed.

55 The deenergization of the high speed relay V also closes its contact members V3, thereby energizing the stopping inductor relay F to stop the car upon its arrival at the third floor.

The deenergization of the high speed relay V 60 also closes its contact members V4, thereby completing a circuit for lighting the down floor lantern 3DLA at the third floor, the circuit extending from the supply conductor L+ (Fig. 5) through the lamp 3DLA, the contact segment 107, the brush 39 now in engagement therewith, the contact members M4 of direction preference relay M and the contact members V4 of the high speed relay V to supply conductor L-. The lighting of the floor lantern serves to notify any passenger 65 who may be waiting at the third floor that the car will stop at that floor on its down trip.

As the car continues at slow speed toward the 70 third floor, the stopping inductor F comes opposite the inductor plate 1DF and is thereby operated to open its contact members F1 (Fig. 4)

for deenergizing the down direction switch D and the brake relay Q to stop the car.

The deenergization of the down direction switch D opens the circuit for the generator field winding 23, thereby deenergizing the hoisting 5 motor 18, and the deenergization of the brake relay Q opens its contact members Q1, thereby deenergizing the brake magnet 6 which operates the brake 5 to stop the car.

The deenergization of the brake relay Q also 10 opens its contact members Q2, thereby deenergizing the slow down holding relay G, the high speed inductor relay E and the stopping inductor relay F.

The matter of lighting the zone arrows for indicating the floor push buttons will now be considered.

The zone arrows for car A are lighted through a ring circuit associated with that car comprising a pair of vertical conductors 110 and 141 20 (Fig. 5). This zone ring circuit is divided into sections by the contact members of the zone relays and each section is connected to an arrow. Each section is also connected to one of the contact segments traversed by the contact 25 brushes 65 and 65a on the up trip and by the contact brushes 85 and 85a on the down trip. When some of the zone relay contact members are opened, the loop circuit is divided into corresponding zones, the number of sections in each zone depending upon which zone relay contact members are opened. The arrows in that zone of the ring circuit connected to the supply conductor L- by the brushes on the floor selector are lighted when the car is conditioned for operation. If only one pair of contact members in the loop circuit are opened, all of the arrows will be lighted, but when two pairs of contact members are opened, only the arrows corresponding to the sections controlled thereby will be lighted. 40

When the car stops at an intermediate floor, one zone brush will engage one contact segment and the other zone brush will engage the next contact segment in advance thereof. Hence two zone relays will then be energized and consequently the contact members on each side of the floor at which the car is standing are opened thereby extinguishing the arrow for that intermediate floor.

However, it should be noted that the arrow at 50 the intermediate floor at which the car is standing will be lighted during that period if and when the corresponding push button at that floor has been operated, because of the self-holding circuit established by the registered call, but 55 when the car is standing at a terminal floor, the arrow will be lighted because the zone brushes are resting on only one contact segment. These two exceptions will not cause any inconvenience in the use of the system, however, because if a 60 car is standing at a floor, a waiting passenger may board it and it will not make any difference whether the arrow for that floor is lighted or dark.

When car A has been standing at the upper terminal and has been controlled for operation and ready to start on its down trip, the brush 85a engages the down contact segment 106, thereby energizing the zone relay 3DZ to open its contact members 3DZ1 (Fig. 5) at the third floor. Inasmuch 70 as no relay was energized to open the circuits for the arrows at the other floors for car A, the down arrows 34 and 33 at the third and second floors respectively and the up arrows 30, 31 and 32 at the first, second and third floors respectively 75

were lighted to indicate that the car A was the nearest car approaching in the direction indicated by the arrows.

For instance, the lighted down arrow 34 beside the floor push button 3DA at the third floor indicates which button should be pressed for the next down car. In a similar manner, the lighted up arrow 31 adjacent the up push button 2UA at the second floor indicates to any waiting passenger that the push button 2UA should be pressed to stop the next up car. In other words, the lighted arrows illuminated the buttons which should be pressed by waiting passengers to stop the next car approaching in the direction in which they desired to go.

Car A being the only car in operation, all of its floor push button arrows were lighted, both in the up and the down direction.

The circuit for lighting each of the arrows for car A while it stood at the upper terminal extended from the supply conductor L+ through each arrow to the zone loop circuit provided by the conductor 110 and thence through conductor 153, contact segment 109, brush 81, and contact members J1 and H2 to the supply conductor L-.

Referring again to car A moving to the third floor, as the car came to the third floor, the advance brush 85 engaged the down contact segment 108 for the second floor thereby energizing the zone relay 2DZ, which opened its contact members 2DZ1 in conductor 113 to control the circuit for the illuminated arrows.

The opening of the contact segments 2DZ1 in addition to the open zone relay contact segments 3DZ1 will prevent the illumination of the arrow 34 at the third floor while car A stands at that floor because brush 81 is slightly in advance of the other brushes on the floor selector and has run off of down contact segment 109 for the third floor. Hence, while the car is standing at the third floor all of the up and the down arrows indicating its floor buttons will be lighted at the various floors except the down arrow for the third floor.

With the car A standing at the third floor on a down trip, it will be assumed that a waiting passenger at the second floor, desirous of making an up trip, presses the up push button 2UA indicated by the illuminated up arrow 31. The operation of this push button will cause the car to stop at the second floor when it next approaches that floor on an up trip.

The pressing of the button 2UA closes the circuit for energizing the call registering relay 2U, which circuit extends from the supply conductor L+ (Fig. 5) through the contact members of push button 2UA, the coil 2U, the contact members 2UP1 of the preventing relay 2UP, the vertical conductor 110 including the contact members 2UZ1 and 1UZ1, horizontal conductor 111, contact segment 112, brush 81, the contact members J1 of auxiliary bypass relay J and the contact members H2 of the bypass relay H to the supply conductor L-.

The energization of the registering coil 2U closes its contact members 2U4 and 2U2 to provide a self-holding circuit for itself, whereby the call may be said to be registered. That is, a single pressing of the button 2UA is sufficient to energize the registering coil 2U and cause it to remain energized until the call is answered by the stopping of the car. The self-holding circuit extends from the supply conductor L+ through contact members 2U4, the coil 2U, the

contact members 2U2 and conductor 113 to supply conductor L-.

The energization of the registering coil 2U also closes its contact members 2U3 which causes the up signal lantern 2ULA at the second floor to light immediately, thereby immediately indicating to the passenger upon the pressing of the button that his stop signal has been registered and that the car will stop for him when it arrives at that floor travelling in the up direction. The circuit for this lamp extends from the supply conductor L+ through the lamp 2ULA, contact members 2U3 and 2U2 and the vertical conductor 113 to supply conductor L-.

The closing of the contact members 2U4 by the energization of the relay 2U also supplies electric current to the contact segment 115, thus preparing a circuit for energizing the stopping relay S when the car approaches the second floor on its up trip.

Assuming that the car A is now started downwardly from the third floor; as previously described, the relays M and J, the holding coil 2C, the stopping relay R, the floor lantern 3DLA, and the zoning relays 3DZ and 2DZ remain energized. As the car starts, the down direction switch D, the brake relay Q and the high speed relay V are energized as before described in starting the car.

The energization of the high speed relay V opens the circuit for the down floor lantern 3DLA and extinguishes it as the car leaves the third floor. The brush 84 leaves the contact segment 103 and thereby deenergizes the stopping relay R as the car leaves.

As the car A continues on down to the second floor, the zone brush 85a leaves the contact segment 106, thereby opening the circuit and deenergizing the zone relay 3DZ. As the car continues downwardly, the brush 85 engages the contact segment 116, thereby energizing the zoning relay 1UZ by a circuit extending from the supply conductor L+ through zoning relay 1UZ, contact segment 115, brush 85, the contact members J4 of the auxiliary bypassing relay J and the contact members H3 of the bypass relay H to the supply conductor L-.

Further movement of the car downwardly causes the brush 85a to leave the contact segment 117, thereby deenergizing the zoning relay 2DZ.

As the car approaches the lower terminal, it is decelerated and stopped by the usual mechanically operated limit switches (not shown). The operation of the limit switch deenergizes the high speed relay V, the down direction switch D, and the brake relay Q, thereby stopping the car at the lower terminal.

The deenergization of the down direction switch and the opening of the limit switch 56 on the floor selector deenergizes the down direction preference relay M thereby energizing the up direction switch N. The circuit for the up direction switch N extends from the supply conductor L+ (Fig. 4) through conductor 101, the contact members of limit switch 57, the coil N and the normally closed contact members M1 of down direction relay M to the supply conductor L-.

The energization of the up direction relay N opens its contact members N1 to lock out the down direction relay M.

The closing of the contact members N2 of the up direction relay N energizes the auxiliary bypass relay for the up direction relay K for the up direction of car A.

The opening of contacts **M2** of the deenergized relay **M** deenergizes the auxiliary bypass relay **J**.

The opening of the contact members **M3** of the down relay **M** deenergizes the car button holding coils **3C** and **2C** thus restoring the car push button **A3** to its normal condition. The subsequent closing of the contact members **N3** of the up direction relay **N** reenergizes these coils for the up direction.

10 The deenergization of the town direction relay **M** and the auxiliary down direction relay **J** cause the contact members **M4**, **J1**, **M5**, **J2**, **M6**, **J3** and **J4** to open thereby electrically disconnecting the brushes on the down cross-head **49** from the car control circuits while the car is on the up trip. On the other hand, the energization of the up direction relay **N** and the up direction auxiliary relay **K** cause the contact members **N4**, **K1**, **N5**, **K2**, **N6**, **K3**, **K4** and **N7** to close thereby electrically connecting the brushes on the up cross-head **48** to the control circuits for the up trip.

Inasmuch as the car is standing at the lower terminal with the brush **60** on the contact segment **120** for the first floor, the closing of the contact members **N4** causes the up floor lantern **1ULA** at the bottom terminal to be lighted by a circuit extending from the supply conductor **L+** (Fig. 5) to the lamp **1ULA**, the contact segment **120**, brush **60**, contact members **N4** and contact members **V4** to the supply conductor **L-**.

Inasmuch as the car is standing at the first floor, the advance brush **65** is disposed in engagement with the up contact segment **121** and the floor selector is energized for the up direction, the zoning relay **2UZ** is energized by a circuit extending from the supply conductor **L+** through coil **2UZ**, contact segment **121**, brush **65**, the contact members **K4** and the contact members **H3** to the supply conductor **L-**. Hence we can see that as the car moves from floor to floor the zoning relays will be energized sequentially but always with overlapping periods of energization so that the lighting of the direction arrows located beside the floor pushbuttons for car **A** keeps traveling along with and in advance of the car and back to the car, but the arrow at any intermediate floor at which the car positioned corresponding to the direction in which the car is traveling is not lighted.

50 The deenergization of the down direction auxiliary relay **J** also opened its contact members **J5** and **J4** thereby deenergizing the zoning relay **1UZ** and restoring that portion of the loop circuit.

The car **A** is now ready for the up trip.

55 The car attendant now moves the car switch **CS** in a clockwise direction to start the car in the up direction. This movement energizes the up direction switch **U** and the relay **Q** by a circuit extending from the line conductor **L+** (Fig. 4) through the contact members **e** and **b** of the car switch **CS** and contact members **D1** and **F2**, the coil **U**, the door and gate contact members **102**, and the coil **Q** to the supply conductor **L+**.

The energization of the brake relay **Q** closes its contact members **Q1** thereby energizing the brake magnet to release the brake to permit movement of the car.

65 The energization of the up direction switch **U** closes its contact members **U1** and **U4** thereby completing a circuit for the field winding **23** of the generator **22**, which circuit extends from the supply conductor **L+** through contact members **U1**, the field winding **23**, the contact members **U4** and resistance **R24** to the supply conductor **L-**.

75 The closing of the contact members **U2** of the

up direction switch completes a self-holding circuit to keep the car in operation until it is stopped by operation of a push button either at one of the floor landings or within the car.

Assuming that the car attendant moves the 5 car switch still further in the clockwise direction to accelerate the car to its normal high speed, then the high speed relay **V** is energized to close its contact members **V1** and short circuit the resistor **R24** for the purpose of causing the car to 10 run to its normal high speed. This circuit extends from supply conductor **L+** through contact members **e** and **a** of the car switch **CS**, contact members **E2**, and the coil **V** to the supply conductor **L-**. 15

The energization of the high speed relay **V** opens its contact members **V4** thereby extinguishing the up direction floor lantern **1ULA** at the first floor.

As the car moves upwardly and approaches the 20 second floor, the brush **63** engages the contact segment **115** thereby energizing the floor button stopping relay **S** to effect the stopping of the car at the second floor. This circuit extends from the supply conductor **L+** (Fig. 5) through the 25 now closed contact members **2U4**, conductor **122**, the contact segment **115**, brush **63**, the contact members **K2** and the coil **S** to the supply conductor **L-**.

Energization of the floor button stopping relay 30 **S** closes its contact members **S1**, thereby energizing the slowdown holding relay **G** for car **A** and the decelerating inductor relay **E**. This circuit extends from supply conductor **L+** through conductor **104**, contact members **S1**, in parallel 35 through the coil **G** and the coil **E**, and thence through the contact members **Q2** to the supply conductor **L-**.

As the car continues its approach to the 40 second floor, the high speed inductor relay **E** comes opposite its cooperating inductor plate **2UE** and is operated thereby to open its contact members **E2** thereby deenergizing the high speed relay **V** to decelerate the car from its high speed to its landing speed. 45

The deenergization of the relay **V** closes its contact members **V4** to maintain the floor lamp **2ULA** in its lighted condition while car **A** stops at the second floor.

The deenergization of the relay **V** also closes 50 its contact members **V3** thereby energizing the stopping inductor relay **F**.

At this point in the movement of the car, the brush **65** engages the contact segment **124** thereby energizing the zoning relay **3UZ** to maintain the 55 correct zone by a circuit extending from the supply conductor **L+** through the coil **3UZ**, contact segment **124**, brush **65**, contact members **K4**, and contact members **H3** to the supply conductor **L-**.

As the car moves in close to the second floor, the energized inductor relay **F** comes opposite the stopping inductor plate **1UF** and is thereby operated to open its contact members **F2**. The opening of the contact members **F2** deenergizes the up direction relay **U** and the brake relay **Q**, which in turn deenergize the slowdown holding relay **G**, the high speed inductor relay **E** and the stopping inductor relay **F**. 60 65

The deenergization of the down direction switch **U** and the brake relay **Q** causes the car to stop at the second floor of its up trip in response to the operation of the floor push button **2UA** by the waiting passenger at the second floor. 70

Assuming now that the waiting passenger 75

boards the car, the door and gate 102 are closed and the car attendant operates the car switch CS to again start the car in the up direction. The operation of the car switch will cause the energization of the up direction relay U, the brake relay Q and the high speed relay V, as previously described. As the car leaves the second floor, the brush 63 leaves the contact segment 115, thereby deenergizing the floor button stopping relay S. 10 The energization of the high speed relay V also opens its contact members V4, extinguishing the floor lantern 2ULA as the car leaves the second floor.

As the car A continues its upward trip the brush 62 engages the contact segment 125 thereby energizing the cancellation relay 126 by a circuit extending from the supply conductor L+ through the now closing contact members 2U4, coil 126, contact segment 125, brush 62, and the contact members N5 to the supply conductor L-. The energization of the cancellation coil 126 opposes the energization of the registering coil 2N4 and thereby deenergizes that coil to cause it to open its contact members to deenergize the coil. 25 The deenergization of the relay 2U opens the contact members 2U4 and thereby restores the relay to its normal nonoperated condition.

Further, as the car A moves upward, the brush 65 leaves the contact segment 121 thereby deenergizing the zone relay 2UZ to maintain the correct zone for that car.

It will be assumed that the car A is operated as previously described until it stops at the top floor and starts down and stops at the third floor. With car A standing at the third floor, as before, the down lantern 3DLA for car A at the third floor is lighted and the following relays are energized; down direction relay M, down bypass relay J, car button holding coils 3C and 2C, zone relay 3DZ and zone relay 2DZ.

The car B will now be placed in operation with car A by closing the master switch B26 (Fig. 4). The closing of this switch connects the driving motor B25 to a source of electrical energy (not shown). The energization of the driving motor operates the generator B22 for supplying current to the hoisting motor B18 to operate the hoisting drum B13. Inasmuch as the separately excited field winding B23 of the generator is not energized, no current flows through the circuit to the hoisting motor and it will remain idle until one of the direction switches for car B is operated to start the car.

A control switch B28 is also closed to place 55 the control circuit for car B in operation by energizing the field winding B19 of the hoisting motor B18, the up direction preference relay BN, the auxiliary by-pass relay BK for the up direction, the push-button holding or registering coils 3BC and 2BC in the car and the up floor lantern 1ULB at the lower terminal for indicating that the car is standing at that floor.

The circuit for the up direction relay BN extends from the supply conductor L+ through conductor 130, the contact members of the motor transmitter B55, the coil BN and the contact members BM1 to supply conductor L-.

The circuit for the auxiliary by-pass relay BK for the up direction extends from the supply conductor L+ through the conductor 130, the contact members BM2, the coil BK and the contact members BH1 to the supply conductor L-.

The circuit for the car button holding coils 3BC and 2BC extends from the supply conductor L+ through conductor 130, the coils 3BC and

2BC and the contact members BN3 of relay N to the supply conductor L-.

The circuit for the lighted lantern 1ULB extends from the supply conductor L+ (Fig. 5) through the lamp 1ULB, the contact segment 132, brush B60, the contact members BN4 and the contact members BV4 to the supply conductor L-.

In considering the lighted arrows for car B, it may be noted that car B has a zone loop or ring circuit provided by the vertical conductors 133 and 136 (Fig. 6) to which the arrows for car B are connected. This ring circuit is practically a duplicate of the zone ring circuit for car A. The ring circuit for car B is controlled by the second pair of contact members on each zone relay; that is each zone relay has two pairs of normally closed contact members, one pair being in the ring circuit for car A and the other pair being in the ring circuit for car B. Thus when any zone relay is energized, it opens one pair of contact members in each circuit. Inasmuch as the zone relays are common to both cars and are controlled by the position of the cars, they operate to divide the lighted arrows into zones, one zone for each car, as will be better understood by continuing the operation of car B.

Inasmuch as the car B is standing at the lower terminal, brush B65 engages the contact segment 127 thereby energizing the zone relay 2UZ by a circuit extending from the supply conductor L+ (Fig. 5), the coil 2UZ, conductor 133 to the contact segment 127 (Fig. 6), the brush B65, the contact members BK4 and the contact members BH3 to the supply conductor L-.

The operation of this zone relay 2UZ opens its contact members 2UZ1 and its contact members 2UZ2, thereby dividing the lighted arrows for car A and the lighted arrows for car B into two zones one zone for car B extending upwardly from car B to the upper terminal and down to car A and the other zone for car Z extending from car A at the third floor to car B at the lower terminal.

The lighted arrow zone for car B comprises the lighted up arrows 36, 37 and 38 indicating respectively the up floor push buttons 1UB at the first floor, 2UB at the second floor and 3UB at the third floor. Therefore, waiting passengers at these floors desiring to travel upwardly should operate the buttons for car B indicated by the illuminated arrows to make car B, which is the nearest car in the corresponding direction, stop for them as it moves upwardly.

The operation of the zone relay 2UZ also causes the down direction arrow 41 beside the push button 4DB for car B at the top floor to be lighted.

The lighted arrow zone for car A, by reason of the operation of the zone relays, extends only from car A at the third floor on its down trip to the lower terminal. In view of the small number of floors in the present installation, this means that the down arrow 33 for car A at the second floor and the up arrow 30 for car A at the lower terminal are lighted. The lighted arrow 33 indicates that waiting passengers at the second floor desiring to go down, should press the down push button 2DA for car A to stop that car as it comes to that floor because it is the nearest car in the direction in which they desire to go.

The circuit for the lighted arrow 33 extends from the supply conductor L+ through the arrow 33, the contact members 2DP1 of preventing relay 2DP, conductor 111, contact segment 112, brush 81, the contact members J1 and H2 to the supply conductor L-.

The lighted arrow 30 is in par-

parallel with the lighted arrow 33, the circuit extending from the supply conductor L+ through arrow 30, the contact members 1U3, conductors 110 and 111, contact segment 112, brush 81 and contact members J1 and H2 to the supply conductor L-.

The circuit for the lighted arrows 33 and 30 cannot extend to any other arrow because the zone relay contact members 2DZ1 and 2UZ1 in the vertical conductor 110 are open.

The circuit for the up lighted arrows 37 and 38 and the down arrow 41 for car B extends as follows: For arrow 37 from supply conductor L+ through arrow 37, contact members 2UP2, conductor 134, contact segment 135, brush B61, contact members BK1 and BH2 to supply conductor L-; for arrow 38 the circuit extends from supply conductor L+ through arrow 38, contact members 3UP2, conductor 137, contact members 3UZ2 in conductor 133 and thence through conductor 134, etc. to the supply conductor L-; and for down arrow 41 the circuit extends from supply conductor L+ through arrow 41, contact members 4BD3, conductor 136, contact members 4DZ2 and again along conductor 136 to the lower part of the drawing where it joins conductor 137 and thence through contact members 3UZ2, conductors 133 and 134, etc. to the supply conductor L-, the three arrows being in parallel. It will be observed that the circuit does not extend to any other arrows for car B because the contact members 3DZ2 and 2UZ2 in the conductor 139 are open by reason of the zone relays 3DZ and 2UZ being energized.

Hence it will be seen that when a passenger comes to a floor to board an elevator car for, say an up direction, all he needs to do is to press the push button indicated by the lighted arrow for the direction he desires to go and that operation of the button will immediately cause the lighting of the signal lantern over the doorway at which the car will stop so that he may at once walk to that door and be ready to board the car when it does come and in addition, the operation of the push button will cause the car corresponding to that button to stop when it arrives at that floor, regardless of the position of the car switch or the actions of the car attendant, unless the car attendant should press the by-pass button to bypass the call.

With both of the cars in operation, it will be assumed that a waiting passenger at the second floor desirous of making an up trip, observes, by the lighted arrow 37, that the push button 2UB should be operated for stopping a car for an up trip. The passenger thereupon presses the button 2UB and thereby registers a stop call for the nearest approaching car in the direction he desires to go.

By the term "nearest approaching car", we mean that car whose direction of travel and distance from said floor will permit the car stopping system (inductor relays, etc.) to stop it at that floor when it arrives thereat. In other words, it means the car which is still capable of being stopped at the floor at which the stop call is registered at the time the call is registered.

The pressing of the button 2UB energizes the floor push button registering relay 2BU by way of a circuit extending from the supply conductor L+ (Fig. 6) through the contact members of button 2UB, the coil 2BU, the contact members 2UP2, conductor 134, contact segment 135, brush B61, contact members BK1 and the contact members BH2 to the supply conductor L-.

The energization of the registering coil 2BU closes its contact members 2BU3 and 2BU4 to complete a self-holding circuit for itself which extends from the supply conductor L+ to the contact members 2BU4, coil 2BU, the contact members 2BU3 and conductor 113 to the supply conductor L-. The closing of the contact members 2BU4 also supplies current through conductor 143 to the contact segment 128 to stop car B when it approaches the second floor on its up trip.

The energization of the registering relay 2BU also closes its contact members 2BU2, thereby immediately illuminating the up floor lantern 2ULB above the door at the second floor corresponding to car B so that the waiting passenger knows immediately that his stop call has been registered, that a car will stop for him in the up direction, and which door will open to permit him to board the car when the car does stop for him so that he may at once walk over to the door indicated by the lighted lantern and be ready to board the car as soon as it stops and the door opens. The circuit for the floor lantern 2ULB extends from the supply conductor L+ (Fig. 6) through floor lantern 2ULB the contact members 2BU2 and 2BU3 and the conductor 113 to the supply conductor L-.

The energization of the registering relay 2BU also closes its contact members 2BU1 (bottom 30 of sheet Fig. 4) thereby energizing the preventing relay 2UP by a circuit extending from the supply conductor L+ through conductor 144, coil 2UP and contact members 2BU1 to the supply conductor L-. The energized relay 2UP opens its contact members 2UP1 in the circuit of up button 2UA at the second floor (Fig. 5) thereby preventing the registration of a call on the up push button 2UA or the lighting of the up arrow 37 at the second floor for car A during the existence of the registered up call at that floor for car B, even though car A passes car B after the call is registered for car B and is first to approach the floor. Thus it is seen that after a call is registered at a floor for a car, the preventing relays prevent the registration of a call or the lighting of the direction arrows of other cars for the same direction at the same floor.

No preventing relays are provided for the terminal floors, but each registering relay at the 50 terminal floors is provided with an extra pair of normally closed contact members which open the line to the zone ring circuit when a call is registered and thereby prevent "sneak" currents through the ring circuits from lighting the 55 arrows of other approaching cars. For instance, if the button 1UB at the lower terminal is operated, its registering relay 1BU opens its contact members 1BU3 and thereby prevents the flow of current from supply conductor L- through conductor 113, and contact members 1BU2 and 1BU3 into the direction arrows for car A if car A should come down past car B after the call is registered for car B.

Assuming now that the car attendant on car 65 B prepares to start the car upwardly, he thereupon operates the car switch BCS to close its contact members b and c to energize the up direction switch BU and the brake relay BQ for car B by a circuit extending from supply conductor L+ through the contact members e and b, the contact members BD1, the contact members BF2, the coil BU, the door and gate interlocks B102, and the coil BQ to the supply conductor L-.

The energization of the brake relay **BQ** closes its contact members **BQ1** thereby energizing the brake magnet **B6** to release the brake **B5**.

- 5 BU closes its contact members **BU1** and **BU4** to supply current to the separately excited field winding **B23** of the generator **B22**, in the same manner as described for car A and the car starts upwardly at slow speed. Further movement of 10 the car switch **BCS** closes its contact members **e** and **a** thereby energizing the high speed relay **BV** to close its contact members **BV1** to eliminate the resistor **BR24** from the generator field winding, thus causing the car to travel at high-speed.

15 The energization of the high-speed relay also closes its contact members **BV4** thereby extinguishing the up-floor lantern **IULB** at the lower terminal as the car leaves that floor.

- 20 The car switch **BCS** may now be returned to its center or neutral position. As the car continues its upward approach to the second floor the brush **B63** engages the contact segment **128** which segment was energized by the registration 25 of the stop call on the button **2UB** second floor and thereby completes a circuit for energizing the floor button stop relay **BS** to stop car B at the second floor.

30 The energization of the stopping relay **BS** closes its contact members **BS1** thereby energizing the slow-down holding relay **BG** and the inductor relay **BE** in preparation to decelerate from high speed.

- 35 As the car continues its approach to the second floor the inductor relay **BE** comes opposite the inductor plate **B2UE** which causes its contact members **BE2** to open, thereby deenergizing the high-speed relay **BV**. The deenergization of the high-speed relay **BV** opens its contact members **BV1** thereby re-inserting the resistor **BR24** in the field circuit of the generator **B22** to decelerate the car to its landing speed.

40 The closing of the contact members **BV4** of the deenergized high speed relay will maintain the floor lantern **2ULB** in a lighted condition while car B stops at the second floor.

45 The deenergization of the high-speed relay also closes its contact members **BV3** thereby energizing the stopping inductor relay **BF**.

- 50 As the car continues its approach to the second floor, the stopping inductor relay **BF** comes opposite the stopping inductor plate **B1UF** which opens its contact members **BF2** thereby deenergizing the up direction switch **BU** and the 55 brake relay **BQ**. The deenergization of the up direction switch and the brake relay deenergizes the generator field and the brake magnet, thereby stopping the car at the second floor. As the doors (not shown) are opened the waiting passenger is ready to step aboard the car for his upward trip.

60 The deenergization of the brake relay **BQ** also opens its contact members **BQ2** thereby de-65 energizing the slow-down holding relay **BG**, the high-speed inductor relay **BE**, and the stopping inductor relay **BF**, thus restoring these relays to their inactive condition.

- 65 It will also be noted that as car B approached 70 the second floor, its brush **B65** engaged the contact segment **129** thereby energizing the zone relay **3UZ** to open its contact members **3UZ2** in the ring circuit for the purpose of extinguishing the direction arrow **37** for the push button 75 **2UB** at the second floor. However that arrow

will remain lighted while the car B is standing at the second floor on its up trip because the self-holding circuit established by the registration of the up call at that floor includes arrow **37**.

75 Car A is standing at the third floor on its down trip and car B is standing at the second floor on its up trip. With the cars in these positions, the down arrow **33** at the second floor and the up arrow **30** at the lower terminal for 10 car A are lighted; and the up arrow **38** at the third floor and the down arrow **41** at the upper terminal for car B are lighted, thereby constituting an advance zone for car A from that car to car B and an advance zone for car B from that 15 car to car A. The circuit for the arrows **33** and **30** of car A remains as previously described. But inasmuch as car B has moved up to the second floor, its brush **B61** has moved to the contact segment **138**. Therefore, the circuit for 20 arrows **38** and **41** now extends as previously described to conductor **137** (lower end of Fig. 6) and thence through that conductor, contact segment **138**, brush **B61**, etc. to the supply conductor **L**.

25 It should also be noted that when an arrow for one car is illuminated at a floor to indicate that the passenger should operate the corresponding push-button, no other push-button at that floor will register a stop call for the same direction; that is, if the passenger presses any other up-button than that corresponding to the lighted up arrow at a floor, a stop call will not be registered. In other words, the operation of the 30 zone relays renders the illuminated or indicated 35 call registering means effective to register calls and renders ineffective all other registering means in the same direction for the other cars at the same floor. This prevention of the registration of stop calls upon non-illuminated buttons follows from the zone system.

40 For instance, with car B now at the second floor, the up arrow **38** for car B at the third floor is illuminated and a call may be registered on the button **3UB** for car B at that floor because 45 the circuit for the registering relay **3BU** may be completed through conductor **137**, contact segment **138**, brush **B61**, etc. However, if the up push-button **3UA** corresponding to the non-illuminated arrow **32** for car A at the third floor 50 is operated, no call will be registered because a circuit cannot be completed for the registering coil **3U** owing to the fact that the contact segment **140** is not engaged by a brush and the section of the ring circuit comprising conductors **141** 55 and **110** with which the third floor up button **3UA** is connected, is dead, by reason of the open condition of the zone relay contact members **3UZ1** and **3DZ1**.

55 When one car passes another car, the operation 60 of the zone relays will transfer the lighting of the arrows in such manner that the zone for each car will still lie in front of that car and extend to the next car in advance thereof. As an illustration of this transfer, it will be assumed that 65 car B is moved up to the upper terminal and then down to the lower terminal where it will remain for some time. With car A on a down trip at the third floor and car B at the lower terminal, the zone relays **3DZ** and **2DZ** are energized by car A and the zone relay **2UZ** is energized by the car B, thereby lighting the down arrow **33** at the second floor and up arrow **30** at the lower terminal for car A, and also lighting the up arrows **36** and **37** at the second and third 75

floors and down arrow 41 at the upper terminal for car B. In other words, the zone for car B extends from car B to the upper terminal and down to car A at the third floor, and the zone 5 for car A extends from car A down to car B, as previously described.

It will be assumed now that car A is run down to the lower terminal and passes car B up to the third floor. This operation of car A causes 10 sequential operation of the zone relays whereby the zone of lighted arrows for car B follows car A down to the lower terminal, but as car A passes car B and moves up to and stops at the third floor, then all the lighted arrows for car B are 15 extinguished by the operation of the zone relays due to the movement of car A except up arrow 37 at the second floor for car B.

With car B remaining at the lower terminal the zone relay 2UZ still remains energized. With 20 car A on an up stop at the third floor, its up brush 65 is on contact segment 142 and its brush 65a is on contact segment 124 thereby completing circuits for energizing the zone relays 3UZ and 4DZ. The zone relay contact members 2UZ1, 25 2UZ2, 3UZ1, 3UZ2, 4DZ1 and 4DZ2 are now open. Inasmuch as the contact brush 61 for car A is now on contact segment 145 a circuit is completed for lighting the down arrows 35, 34 and 33 for car A at the fourth, third and second floors, 30 thereby indicating to the intending down passengers at those floors that they should press the buttons indicated for car A to stop the nearest approaching car for a down trip. It may be noted that the up arrow 32 for car A at the lower terminal is also lighted, but as explained before, this will not occasion any confusion in the system.

Inasmuch as the brush B61 for car B is still on the up contact segment 135 the up arrow 37 at the second floor and the up arrow 36 at the lower 40 terminal for car B are lighted, but because of the open contact members 2UZ2 and 3UZ2 in the zone ring circuit, no other arrows for car B are lighted.

Hence it is seen that the down signal arrows 35, 34 and 33 for car A are lighted to define a 45 zone from car A to car B and that the up arrow 37 at the second floor is lighted to define a zone from car B to car A. Therefore, if waiting down passengers at any intermediate floor desire a car to stop for them, they will press the down 50 buttons indicated by the lighted arrows for car A; and if an up passenger at the second floor desires to have an up car stop for him he will press the button 2UB indicated by the lighted arrow 37 for car B. The passengers at the lower 55 terminal and at the third floor who desire to move up can board the cars as they stand at those floors.

An assumed operation of the bypassing means whereby a car attendant may cause his car to 60 bypass a stop call registered on a floor push button, without answering the call and at the same time cause the registered call to be transferred to the nearest approaching car in the corresponding direction, is as follows:

65 It will be assumed that car B is left in its position at the lower terminal and that car A is moved from the third floor to the upper terminal. With car A at the upper terminal, its down direction preference relay M and its auxiliary bypass relay 70 J for the down direction are energized. The zone relay 3DZ is also energized by the position of car A.

Assuming now that a waiting passenger at 75 the second floor desires to travel downwardly and, therefore, presses the down push button 2DA

indicated by the lighted arrow 33 for car A at the second floor to cause the nearest approaching car to stop. The pressing of the button 2DA completes a circuit for energizing the stop call registering relay 2D, which circuit extends from 5 the supply conductor L+ through the contact members of the push button 2DA, the coil 2D, the contact members 2DPI, the vertical conductor 110 including the contact members 2DZ1 and conductor 153 to the contact segment 109, contact brush 81 (now on contact segment 109 because of the position of car A at the upper terminal), the contact members J1 and H2 to the supply conductor L-. The energization of the registering relay 2D closes its contact members 2D3 15 and 2D4 to complete a self-holding circuit for itself. The closing of the contact members 2D2 of the energized relay 2D completes a circuit for lighting the floor lantern 2DLA to indicate to the passenger that his stop call has been registered and that a car will stop for him.

Although the operation of the push button 2DA has registered the passenger's stop call for car A, it will be assumed that the attendant on car A desires to run his car as an express from the 25 upper terminal to the lower terminal and thereby avoid answering any registered down calls at the intervening floors. In order to accomplish this result, the car attendant starts the car as previously described and at the same time presses 30 the bypass button 43 in the car to effect the transfer of any registered calls. The pressing of the bypass button 43 (which must be continued during the bypassing period) energizes the bypass relay H to open its contact members H1, H2, H3 35 and close the contact members H4 and H5, by a circuit extending from the supply conductor L+ (Figure 4) through conductor 101, the contact members of bypass button 43 and the coil H to the supply conductor L-. 40

The opening of the contact members H1 de-energizes the auxiliary bypass relay J to open its contact members. The opening of the contact members J3 (Fig. 5) prevents current from flowing through the contact brush 85a and the contact segment 106 to the zone relay 3DZ, thereby deenergizing that relay. The deenergization of the zone relay 3DZ closes its contact members 3DZ2 thus completing a circuit for lighting the arrows at each floor for car B to define the 50 zone for car B as now extending up to the upper floor and then down to the lower terminal.

The opening of the contact members J1 prevents current flowing through the brush 81 of car A to the zone loop circuit of car A for lighting 55 the indicating arrows of that car at the floors. Consequently all the lighted arrows for car A are extinguished and none of them will be lighted again until the bypass button 43 is released.

However the lighted down arrow 33 at the 60 second floor will remain lighted until the car nears that floor by reason of the closed condition of the contact members 2D3 on the registering relay.

The energization of the bypass relay H also 65 closes its contact members H4 for electrically connecting the brushes 86 and 87 for bypassing purposes.

As the car A on its down trip nears the 70 second floor, the brushes 86 and 87 engage the down contact segments 149 and 150 corresponding to the second floor and thereby energize the bypassing transfer relay 2DT to effect the transfer of the registered call from the registering relay 2D of car A to the registering relay 2BD for car 75

B. This circuit extends from the supply conductor L+ (Fig. 5) through the contact members 2D4, conductor 154, contact segment 149, brush 86, contact members H4 and M1, brush 87, contact segment 150 and coil 2DT to the supply conductor L-.

The energization of the relay 2DT closes its contact members 2DT2 thereby energizing the down push button registering relay 2BD at the 10 second floor, by a circuit extending from the supply conductor L+ (Fig. 6) through the contact members 2DT2, the registering coil 2BD, the contact members 2DP2, vertical conductor 139 of the zone ring circuit, and around through the contact members 2DZ2, 3DZ2, conductor 136, the contact members 4DZ2 leading to conductor 136, conductor 134, contact segment 135, brush B61 and contact members BK1 and BH2 to the supply conductor L-.

The down stop call at the second 20 floor is now transferred to and registered on the registering relay 2BD for car B at the second floor and it will cause car B to stop at that floor when that car approaches on its next down trip.

The energization of the call registering relay 25 2BD closes its contact members 2BD2, 2BD3 and 2BD4, thereby providing a self-holding circuit for itself and also providing a circuit for energizing the down signal lamp 2DLB for car B at the second floor to notify the waiting passenger at that 30 floor that car B will stop for him.

The call is now transferred to car B so that the waiting passenger at the second floor knows that car B will stop for him and the down contact segment 155 is energized so that when the brush B83 35 of car B engages it, car B will be stopped at the second floor.

It should be noted here that, as car A approaches the second floor stop, its brush 83 engages the energized contact segment 149 but its 40 stopping relay S is not energized thereby because the contact members J2 in the stopping relay circuit have been opened by the operation of the deenergized auxiliary bypassing relay J. Therefore, car A does not stop at the second floor.

As car A passes the second floor, the brushes 45 86 and 87 leave the contact segments 147 and 148 thereby opening the circuit for and deenergizing the transfer relay 2DT.

Also as car A passes the second floor on the 50 press down trip, its contact brush 82 engages the contact segment 151, thereby energizing the restoring coil 156 to restore the registering relay 2D for car A to its unoperated condition by way of a circuit extending from the supply conductor L+ 55 through the closed contact members 2D4, coil 156, contact segment 151, brush 82, contact members M5 to the supply conductor L-.

The deenergization of the registering relay 2D for car A opens its contact members 2D2 and 2D3, thereby 60 destroying its self-holding circuit and also extinguishing the down floor lantern 2DLA for car A at the second floor. Thus the passenger at the second floor will know that the call has been transferred to car B and will not be confused by 65 two lighted floor lanterns.

It will be assumed now that car A is run on down to the lower terminal and left at that terminal. Inasmuch as the transfer relay 2DT is not now energized and the car attendant is not pressing 70 the bypassing button 43, the lighted arrow zones for car A will become effective again.

Assuming now that car B is run up to the upper terminal and then down to the second floor, as it 75 approaches the second floor, its contact brush B83 engages the energized contact segment 155 and

thereby energizes its floor button stopping relay BS by way of a circuit extending from the supply conductor L+ through the contact members 2BD4, conductor 157, contact segment 155, brush B83, contact members BJ2 and the coil BS to the 5 supply conductor L-.

As previously described, the energization of the floor button stopping relay BS causes the inductor relays BE and BF to effect the deceleration and stopping of the car at the second floor. Thus the transfer of the stop call 10 from car A to car B has been completed and has caused car B instead of car A to stop at the second floor.

In some installations it may be desirable to omit the zone arrows and the individual push buttons 15 for each car at each floor and to substitute therefor a control switch for each push button switch with a single mechanical means for simultaneously closing all of the up control switches and a second mechanical means for simultaneously 20 closing all of the down control switches. It is obvious that, if all the up control switches or push button switches at a floor are closed simultaneously, only the nearest approaching car for the up direction will be stopped at that floor, as the 25 switches which are not conditioned for operation by the zone relays will have no effect on the cars to which they correspond while the switch which has been conditioned for operation will be effective as usual.

In Figs. 2 and 3, we have shown a suitable means for simultaneously closing all of the switches for one direction at a floor. This means comprises a base 160 upon which a plurality of contact posts 161 (one for each car in the up 35 direction) in position to be engaged by cooperating contact fingers 162. The contact fingers are mounted upon a non-conducting plate 163 pivotally supported upon a riser 164 which, in turn, is mounted upon the base plate 160. A 40 spring 165 is provided for biasing the plate 163 and the contact fingers disposed thereon away from engagement with the contact posts. The base 160 is provided with side walls 166 upon which is mounted a cover plate 167. A suitable 45 push button 168 is mounted in the cover plate 167 in position to so engage the outer face of the plate 163 that pressing of the push button will move the plate inwardly against the biasing spring 165 and cause the contact fingers to engage their cooperating contact posts. The individual up circuits for the cars may be connected to these contact posts and their cooperative contact fingers in the same manner as they are connected to the push button switches. 55

If the push button 169 is depressed, all of the up control switches corresponding to the up push buttons 2UA, 2UB, etc., will be closed but only that switch will be effective which is conditioned or prepared for operation by the position of the next approaching car in the up direction.

The down control switches may be operated by the push button 169 and inasmuch as they are constructed in the same manner as those for 60 the up direction, a further description thereof will not be given.

When the push button device 27 shown in Fig. 1 is employed in an elevator system embodying our invention, it is obvious that the pressing of 70 either the up button 168 or the down button 169 will ensure the operation of the control device or switch for the next approaching car in the appropriate direction and will cause the instant lighting of the corresponding signal lamp and 75

the later stopping of the corresponding car when it comes to the corresponding floor.

It will also be obvious that when the push button device shown in Figs. 2 and 3 is substituted for the push button device 27 of Fig. 1, no lighted arrows will be needed to indicate which button should be operated because the common means or button for either direction will suffice to close all the control switches for that direction and in so doing will of course close the control switch conditioned by the zone relays and the next approaching car for that direction. The fact that the other control switches for that direction are also closed will have no effect upon the system because their circuits are not conditioned for effective operation. Hence it will be understood that our system may be operated with the floor button device 27 shown in Fig. 1 or with the device shown in Figs. 2 and 3.

It is therefore seen that we have provided an improved signal and control system for elevators in which a waiting passenger at a floor upon pressing a button to register a stop call for a car, immediately receives a signal indicating that his stop call has been registered, that a car will stop for him and the hatchway door at which the car will stop so that he may immediately walk to the indicated door and be ready to board the car when it stops and the doors open.

It will also be seen that we have provided a system in which the operation of the cars will cause a travelling zone to indicate which car is the nearest approaching car for the direction desired.

Furthermore, it will be seen that we provided a system in which a car attendant may run his car as an express car and thereby avoid having it stopped by any outside or floor button call and, when any floor button calls exist, cause them to be transferred to the next nearest approaching car, so that it will stop for the waiting passengers. Not only will the call be transferred but it will be so transferred that the passengers will not be confused as to which car will stop for them.

Although we have illustrated and described our invention as embodied in only one elevator system and a slight modification thereof, it is to be understood that many changes therein and modifications thereof may be made without departing from the spirit and scope of the invention.

We claim as our invention:

1. In an elevator system for operating a plurality of cars past a floor, a plurality of control devices at the floor, one for each car, means responsive to the operation of a control device for stopping the corresponding car at the floor, and means responsive to operation of the cars for indicating which control device should be operated to stop the nearest approaching car.

2. In an elevator system for operating a plurality of cars past a floor, a plurality of signal devices at the floor, one for each car, a plurality of control devices at the floor, one for each car, means responsive to operation of the cars for indicating which control device should be operated to stop the nearest approaching car at the floor and means responsive to operation of an indicated control device for immediately operating the signal device of the car corresponding to the indicated control device and for stopping that car when it arrives at the floor.

3. In an elevator system for operating a plurality of cars past a plurality of floors, a plurality

of signal devices at each floor, one for each car in the up direction and one for each car in the down direction, a plurality of control devices at each floor, one for each car in the up direction and one for each car in the down direction, means responsive to operation of the cars for indicating which control device should be operated at each floor for stopping the nearest approaching car in the desired direction, and means responsive to operation of indicated control devices for stopping corresponding cars at corresponding floors in the direction desired, regardless of the order of operation of the indicated control devices.

4. In an elevator system for operating a plurality of cars past a floor, a plurality of control devices at the floor, one for each car, means responsive to operation of the cars for rendering effective the control device corresponding to the nearest approaching car, and means responsive to operation of the effective control device for stopping the car corresponding thereto when it arrives at the floor.

5. In an elevator system for operating a plurality of cars past a floor, a plurality of control devices at the floor, one for each car, means responsive to operation of the cars for rendering effective the control device corresponding to the nearest approaching car and for rendering ineffective the other control devices, and means responsive to the operation of an effective control device for stopping the car corresponding thereto when it arrives at the floor.

6. In an elevator system for operating a plurality of cars past a plurality of floors, a plurality of control devices at each floor, one for the up direction and one for the down direction for each car, means responsive to operation of the cars for rendering effective at each floor a control device for the nearest approaching car for the up direction and a control device for the nearest approaching car in the down direction, and means responsive to operation of an effective control device for stopping the corresponding car upon its arrival at the floor of the operated control device.

7. In an elevator system for operating a plurality of cars past a floor, a plurality of signal devices at the floor, one for each car, a plurality of control devices at said floor, one for each car, means responsive to operation of the cars for indicating which control device should be operated to stop the nearest approaching car at the floor and for rendering the non-indicated control devices ineffective, and means responsive to operation of an indicated control device for immediately operating the signal device of the car corresponding to the indicated control device and for stopping that car when it arrives at the floor.

8. In an elevator system for operating a plurality of cars past a floor, a plurality of control devices at the floor, one for each car, means responsive to operation of the cars for rendering effective the control device corresponding to the nearest approaching car and for rendering ineffective the other control devices, means responsive to the operation of an effective control device for stopping the car corresponding thereto when it arrives at the floor and means common to all of the control devices for operating them simultaneously.

9. In an elevator system for operating a plurality of cars past a plurality of floors, a plurality of control devices, one for the up direction and one for the down direction for each car at each floor, means responsive to operation of the cars

for rendering effective at each floor the up control device of the nearest approaching car for the up direction and the control device of the nearest approaching car for the down direction and 5 for rendering ineffective the other control devices at that floor, means responsive to operation of an effective control device for stopping the corresponding car when it arrives at the floor of said operated device in the corresponding direction, 10 means at each floor for simultaneously operating all the up control devices at that floor, and means at each floor for simultaneously operating all the down control devices at that floor.

10. In an elevator system for operating a 15 plurality of cars past a plurality of floors, a plurality of control devices, one for the up direction and one for the down direction for each car at each floor, means responsive to operation of the cars for rendering effective at each 20 floor the up control device of the nearest approaching car for the up direction and the control device of the nearest approaching car for the down direction and for rendering ineffective the other control device at that floor, means responsive to operation of an effective control device for stopping the corresponding car when it arrives at the floor of said operated device in the 25 corresponding direction, a single push button at each floor for simultaneously operating all the up control devices at that floor, and a single push button means at each floor for operating all the down control devices at that floor.

11. In an elevator system for operating a 35 plurality of cars past a floor, a plurality of control devices at the floor, one device for each car, means responsive to operation of the cars for rendering effective the control device of the nearest approaching car, means responsive to operation of the effective control device for stopping 40 the car corresponding to the effective control device when that car arrives at the floor and for preventing the said operation from stopping another car in the system.

12. In an elevator system for operating a 45 plurality of cars past a plurality of floors, a plurality of control devices, one for the up direction and one for the down direction for each car at each floor, means responsive to operation of the cars for rendering effective at each floor the 50 up control device of the nearest car for that direction and the down control device of the nearest car for that direction, and means responsive to operation of an effective control device for stopping the corresponding car when it arrives 55 at the floor corresponding to the operated device and for preventing said operation from stopping another car in the system.

13. In an elevator system for operating a 60 plurality of cars past a plurality of floors, a plurality of control devices, one for the up direction and one for the down direction for each car at each floor, means responsive to operation of the cars for rendering effective at each floor the up control device of the nearest car for 65 that direction and the down control device of the nearest car for that direction and for rendering ineffective the other control devices, means responsive to operation of an effective control device for stopping the corresponding car when it arrives 70 at the floor corresponding to the operated device and for preventing said operation from stopping another car in the system.

14. In an elevator system for operating a 75 plurality of cars past a plurality of floors, a plurality of control devices, one for the up direc-

tion and one for the down direction for each car at each floor, a plurality of registering devices one for each control device and responsive to operation thereof for immediately registering operation of that control device, means responsive to operation of the cars for rendering effective the registering device of the up control device for the nearest approaching car for that direction at each floor and for rendering effective the registering device of the down control device 10 for the nearest approaching car for that direction at each floor, and means responsive to operation of the registering device of an effective control device for stopping the corresponding car when it arrives at the corresponding floor and 15 for preventing said operation of said registering device from stopping another car in the system.

15. In an elevator system for operating a 20 plurality of cars past a floor, a plurality of devices for registering calls to stop the cars at the floor, one for each car, means responsive to operation of the cars for rendering effective the registering device corresponding to the nearest approaching car, means responsive to the registration of a stop call on the effective registering device for stopping the corresponding car when it arrives at the floor, and means for cancelling the registration of a call on the effective registering device and registering that call on the 25 registering device for the next approaching car 30 and rendering the last named registering device ineffective to operate.

16. In an elevator system for operating a 35 plurality of cars past a floor, a plurality of signal devices at the floor, one for each car, a plurality of means for registering calls to stop the cars at the floor, one for each car, means responsive to operation of the cars for rendering effective the registering means corresponding to the nearest approaching car and for rendering 40 ineffective the registering means corresponding to the other cars, and means for cancelling a stop call registered on an effective registering means and for rendering said effective registering means ineffective and for registering said cancelled call 45 on the registering means of the next following car.

17. In an elevator system for operating a 50 plurality of cars past a floor, a plurality of means for registering stop calls, one registering means for each car, a stopping means for each car, each stopping means being responsive to the registration of a call for a car and the position of that car for stopping that car at the floor, a plurality of signal devices at the floor, one for 55 each car, each signal means being responsive to the registration of a call for its car for indicating that the call has been registered and that the car corresponding to the registering means will stop at the floor, means responsive to operation of the cars for rendering effective that registering means corresponding to the nearest approaching car and for rendering the other registering means ineffective, means for transferring a call registered by an effective registering means 60 for one car to the registering means of the next following car and to render the last named registering means effective to immediately operate the signal device of said next following car and to stop it when it arrives at the floor and to cancel the signal device of the car for which the call was first registered, and means for restoring the first named operated registering means to its unoperated condition.

18. In an elevator system for operating a plu- 75

5 rality of cars past a plurality of floors, an up zone indicating device and a down zone indicating device for each car at each floor and means responsive to the position of the cars for operating the indicating devices corresponding to each car and the direction it will move to answer calls between that car and the next car ahead of it and for rendering inactive the other indicating devices.

10 19. In an elevator system for operating a plurality of cars past a plurality of floors, an up call registering means and a down call registering means, for each car at each floor, and means responsive to operation of the cars for rendering effective for the registration of calls the registering means for each car in the direction in which the car will move to answer registered calls at each floor between that car and the next preceding car and for rendering the other registering means for said "that" car ineffective to register calls.

20 20. In an elevator system for operating a plurality of cars past a plurality of floors, a plurality of ring circuits, one for each car, each ring circuit comprising a plurality of sections, means responsive to operation of the cars for dividing each ring circuit into a plurality of zone portions including one or more of said sections in accordance with the number and position of the 25 cars, and means responsive to the position of each car for connecting to a source of electric energy that zone portion of its ring circuit corresponding to the floors between that car and the next car ahead of it.

30 21. In an elevator system for operating a plurality of cars past a plurality of floors, a plurality of ring circuits, one for each car and each ring circuit comprising a plurality of sections, a plurality of electromagnetic devices operably 35 responsive to operation of the cars for dividing each ring circuit into a plurality of zone portions including one or more of said sections in accordance with the number and position of the cars, and means responsive to the position of each car for connecting to a source of electric 40 energy that zone portion of its ring circuit corresponding to the floors between that car and the next ahead of it.

45 22. In an elevator system for operating a plurality of cars past a plurality of floors, a plurality of ring circuits, one for each car and each ring circuit including a plurality of sections, a plurality of zone indicating means for each car, means connecting the zone indicating devices for different floors and different directions for each car to different sections of the ring circuit for that car, means responsive to operation of the cars for dividing each ring circuit into a plurality of zone portions including one or more sections 50 in accordance with the number and position of the cars, and means responsive to the position of each car for connecting to a source of electric energy that zone portion of its ring circuit corresponding to the floors between that car and the next car in front of it.

55 23. In an elevator system for operating a plurality of cars past a plurality of floors, a plurality of ring circuits one for each car and each ring circuit including a plurality of sections, a plurality of call registering means for each car, means connecting the call registering means for each car to different sections of the ring circuit for that car, means responsive to operation of the cars for dividing each ring circuit into a plurality of zone portions including one or more sec-

tions in accordance with the number and position of the cars, and means responsive to the position of each car for connecting to a source of electric energy that zone portion of its ring circuit corresponding to the floors between that car and the next car in front of it, whereby the call registering relays for said floors in the direction of travel of that car are rendered effective to register stop calls.

10 24. In an elevator system for operating a plurality of cars past a plurality of floors, a plurality of control devices for operation to effect the stopping of the cars at the floors, one for the up direction and one for the down direction for each car at each floor, and means responsive to 15 operation of the cars for rendering effective for operation at each floor the up control device of the next car for up service at that floor and the down control device of the next car for down service at that floor.

20 25. In an elevator system for operating a plurality of cars past a floor, a plurality of control devices at the floor, one device for each car, means responsive to operation of the cars for rendering effective the control device of the nearest approaching car, means responsive to operation of the effective control device for stopping the car corresponding to the effective control device when that car arrives at the floor and for preventing the other control devices from becoming effective 25 until the car of the operated effective control device answers said operated control device.

30 26. In an elevator system for operating a plurality of cars past a plurality of floors, a plurality of control devices, one for the up direction and one for the down direction for each car at each floor, a plurality of call registering devices, one for each control device and responsive to operation thereof for immediately registering operation of that control device, means responsive to operation of the cars for rendering effective the registering device of the up control device for the nearest approaching car for that direction at each floor and for rendering effective the registering device for the down control device for the 35 nearest approaching car for that direction at each floor, and means responsive to operation of an effective registering device for stopping the corresponding car when it arrives at the corresponding floor and for preventing the other registering 40 devices for the same direction for the same floor from becoming effective until said operated registering device is restored to unoperated condition.

45 27. In an elevator system for operating a plurality of cars past a floor, a plurality of control devices at the floor, one for each car, the control devices being disposed in a single group for ready operation by waiting passengers, means responsive to operation of the control devices for stopping the corresponding cars at the floor, and means responsive to operation of the cars for indicating which control device should be operated to stop the nearest approaching car.

55 28. In an elevator system for operating a plurality of cars past a floor, a plurality of control devices at the floor, one for each car, said control devices being disposed in a group readily accessible for operation by waiting passengers, means responsive to operation of a control device for stopping the corresponding car at the floor, an 60 indicating means associated with each control device, and means responsive to operation of the cars for operating the indicating devices to indicate which control device should be operated to stop the nearest approaching car.

29. In an elevator system for operating a plurality of cars past a floor, a plurality of signal devices at the floor, one for each car, a plurality of control devices at the floor, one for each car, 5 said control devices being disposed in a group readily accessible for operation by waiting passengers, an individual indicating device associated with each control device, means responsive to operation of the cars for operating the indicating devices to indicate which control device should be operated to stop the nearest approaching car at the floor, and means responsive to operation of an indicated control device for immediately operating the signal device of the car corresponding 10 to the indicated control device and for stopping that car when it arrives at the floor.
30. In an elevator system for operating a plurality of cars past a plurality of floors, a plurality of signal devices at each floor, one for each 15 car in the up direction and one for each car in the down direction, a plurality of control devices at each floor, one for each direction for each car, the control devices at each floor being disposed in a single group readily accessible to operation by 20 waiting passengers at that floor, an up indicating device associated with each of the up control devices, a down indicating device associated with each of the down indicating devices, means responsive to operation of the cars for operating 25 the indicating devices to indicate which control device should be operated at each floor for stopping the nearest approaching car in the desired direction, and means responsive to operation of the indicated control devices for stopping corresponding cars at corresponding floors in the direction desired, regardless of the order of operation 30 of the indicated control devices.
31. In an elevator system for operating a plurality of cars past a plurality of floors, a plurality 35 of control devices at the floors, one for each direction for each car, the control devices at each floor being disposed in a single group readily accessible for operation by waiting passengers at that floor, an up indicating arrow disposed adjacent to each up control device, a down indicating arrow disposed adjacent to each down control device, means responsive to operation of the cars for illuminating the indicating arrows to indicate which control device should be operated at each 40 floor for stopping the nearest approaching car in the desired direction, and means responsive to operation of the indicated control devices for stopping corresponding cars at corresponding floors in the direction desired, regardless of the order of operation of the indicated control devices.
32. In an elevator system for operating a plurality of cars serving an upper terminal floor and a lower terminal floor and intermediate floors, a 45 down control device at the upper terminal floor and at each of the intermediate floors for each car, an up control device at the lower terminal floor and at each of the intermediate floors for each car, an up indicator disposed adjacent to each up control device, a down indicator disposed adjacent to each down control device, the indicators and the control devices at each floor being disposed in a group readily accessible for observation and operation by waiting passengers, 50 means responsive to operation of the cars for operating the indicators to indicate at each floor which control device should be operated for stopping the nearest approaching car for service at that floor in the direction desired regardless of 55 the direction of movement of said car, and means

responsive to operation of the indicated control devices for stopping corresponding cars at corresponding floors in the direction desired regardless of the order of operation of the indicated control devices.

33. In an elevator system for operating a plurality of cars past a plurality of floors, a plurality of control devices one for the up direction and one for the down direction for each car at each floor, a plurality of registering devices one 10 for each control device and responsive to operation thereof for immediately registering operation of that control device, means responsive to operation of the cars for indicating which control device at each floor should be operated for 15 stopping the nearest approaching car in the desired direction at that floor, and means responsive to operation of the registering device of an indicated control device for stopping the corresponding car when it arrives at the corresponding 20 floor in the corresponding direction.

34. In a control system for operating a plurality of cars past a plurality of floors, means to start each car and means to stop each car at any floor; a plurality of control devices associated 25 with each floor, one for each car, an indicating device associated with each of the control devices at each floor, means common to all the cars and responsive to operation thereof for operating the indicating device associated with the control device at any floor for only the nearest approaching car, and means responsive to an operation of an indicated control device for causing an operation of the stopping means for the corresponding car when the car subsequently approaches 30 within stopping distance of the floor of the operated control device, said control devices and said indicating devices being arranged in horizontal rows in the order corresponding to the order of the respective cars.

35. In an elevator system for operating a car serving a plurality of floors, a plurality of contact segments, a pair of contact brushes disposed to engage the contact segments, means responsive to operation of the car for moving the brushes 40 along the contact segments in accordance with the movements of the car past the floors, and means responsive to operation of the car in one direction for electrically connecting said brushes and to operation of the car in an opposite direction for electrically disconnecting said brushes.

36. In an elevator system for operating a car serving a plurality of floors, a plurality of contact segments, a pair of contact brushes disposed to engage the contact segments for connecting an 55 electrical circuit for the system, means responsive to operation of the car for moving the brushes simultaneously and sequentially along the contact segments in accordance with the movements of the car at the floors, and means responsive to operation of the car in one direction for electrically connecting said brushes in a common circuit and to operation of the car in an opposite direction for electrically disconnecting one brush from the other brush.

37. In an elevator control system for operating a plurality of cars past a plurality of floors; a plurality of registering relays, one for each car for each floor, a zone relay for each floor; a circuit for each car interconnecting the registering relays of that car, said interconnecting circuit for each car including a pair of normally closed contact members of each zone relay; means operable in accordance with the movement of each car for energizing a zone relay cor- 75

responding to the position of that car and for connecting said interconnecting circuit to a supply circuit to energize said registering relays, said normally closed zone relay contact members being so disposed that the registering relays for any given car can be energized only for floors between the position of said car and the position of the next car in advance of said car; and means responsive to any energized registering relay to cause the car controlled by that relay to slow down and stop at the floor corresponding to said energized relay when said car in its movements approaches said floor.

38. In an elevator installation; a floor; a plurality of elevator cars serving said floor; a plurality of hall buttons at said floor, one for each of said cars; means individual to each hall button, and responsive to operation of the corresponding hall button, for registering, for the elevator car for which such hall button is provided, a demand for elevator service; and means for preventing the registration of such demands from said floor for more than one of said cars at the same time. 10 5
